(57) **CLAIM**

The ornamental design for a flexible lighting apparatus, as
shown and described.

DESCRIPTION

FIG. 1 is a perspective view of a flexible lighting apparatus, in
accordance with the present invention.

FIG. 2 is a front view (distal end) of a flexible lighting
apparatus, in accordance with the present invention.

FIG. 3 is a top view of a flexible lighting apparatus, in
accordance with the present invention.

FIG. 4 is a rear view (proximal end) of a flexible lighting
apparatus, in accordance with the present invention.

FIG. 5 is a bottom view of a flexible lighting apparatus, in
accordance with the present invention.

FIG. 6 is a side view of a flexible lighting apparatus, in
accordance with the present invention; and,

FIG. 7 is an opposing side view of a flexible lighting
apparatus, in accordance with the present invention.
